TELEVISION RECEIVER

Frank M. Grunwald, Syracuse, N.Y., assignor to General
Electric Company, a corporation of New York

Filed Feb. 18, 1963, Ser. No. 73,593

Term of patent 3½ years

(Cl. D56—4)

FIG.1

FIG.2

FIG.3

FIG.4

FIGURE 1 is a perspective view of a television receiver, embodying my new design;

FIGURE 2 is a side elevational view;

FIGURE 3 is a top plan view; and

FIGURE 4 is a rear elevational view thereof.

The dominant features of my design reside in the portions shown by means of full lines.

I claim:

The ornamental design for a television receiver, as shown and described.
